John T. Jackson, Louisville, Ohio, assignor to Old King Cole Displays, Inc., Louisville, Ohio, a corporation of Ohio

Application August 27, 1953, Serial No. 26,607

Term of patent 14 years

(Cl. D44—29)

To all whom it may concern:

Be it known that I, John T. Jackson, a citizen of the United States, residing at Louisville, in the county of Stark and State of Ohio, have invented a new, original, and ornamental Design for a Beverage Measure, of which the following is a specification, reference being had to the accompanying drawing, forming part thereof.

Figure 1 is a perspective view of a beverage measure showing my new design;

Fig. 2 is a plan view thereof; and
Fig. 3 is a side elevation thereof.

I claim:

The ornamental design for a beverage measure, substantially as shown.
